(57) **CLAIM**

The ornamental design for a motor vehicle and/or toy replica, as shown and described.

DESCRIPTION

FIG. 1 is a left side view of a motor vehicle and/or toy replica showing my new design;

FIG. 2 is a right side view thereof;

FIG. 3 is a front view thereof;

FIG. 4 is a rear view thereof;

FIG. 5 is a top view thereof; and,

FIG. 6 is a bottom view thereof.

The drawings include CAD lines that represent contour and not surface decoration.

The broken lines illustrate structure or features which form no part of the claimed design.

The faded portions within the broken lines form no part of the claimed design.
